H. L. BENNETT

Des. 169,654

PAPER CUP HOLDER OR SIMILAR ARTICLE

Filed July 30, 1952

FIG 1

FIG 2

Inventor
Herbert L. Bennett

By Bill Sherman, Kansas City, ATTY

UNITED STATES PATENT OFFICE

169,654

PAPER CUP HOLDER OR SIMILAR ARTICLE

Herbert L. Bennett, Easton, Pa., assignor to Dixie Cup Company, Easton, Pa., a corporation of Delaware

Application July 30, 1952, Serial No. 20,856

Term of patent 14 years

(Cl. D44—9)

To all whom it may concern:

Be it known that I, Herbert L. Bennett, a citizen of the United States, and a resident of the city of Easton, in the county of Northampton and State of Pennsylvania, have invented a new, original, and ornamental Design for a Paper Cup Holder or Similar Article, of which the following is a specification, reference being had to the accompanying drawing, forming a part thereof.

On the drawing:

Figure 1 is a plan view, of a paper cup holder or similar article, embodying my new design, and

I claim:

The ornamental design for a paper cup holder or similar article, substantially as shown.

HERBERT L. BENNETT.
